(57) **CLAIM**

The ornamental design for a fuel dispenser, as shown and described.

DESCRIPTION

FIG. 1 is a perspective view from above illustrating the front and right side view of a first exemplary embodiment of the fuel dispenser;

FIG. 2 is a perspective view illustrating the front and left side view of the fuel dispenser of FIG. 1;

FIG. 3 is a front view of the fuel dispenser of FIG. 1;

FIG. 4 is a rear view of the fuel dispenser of FIG. 1;

FIG. 5 is a right side view of the fuel dispenser of FIG. 1; and, FIG. 6 is a left side view of the fuel dispenser of FIG. 1.

Where applicable, elements are shown in broken lines herein for illustrative purposes only, and form no part of the claimed design. Moreover, the bottom and the top of embodiments of the fuel dispenser of FIGS. 1-6 form no part of the claimed design.
